ELECTRIC PLUG CONSTRUCTION

Albert E. Grant, New York, N. Y.

Application June 8, 1932, Serial No. 615,979

5 Claims. (Cl. 200—51)

My invention relates to electric plug constructions and one object of my invention is to provide an improved switch plug of simple construction, the several parts of which may be cheaply made and easily assembled.

Another object is to provide an attachment plug having improved spring sockets therein adapted to receive and firmly grip the prongs of a leg plug or the prong-like attachment terminals of devices such as sad irons.

A further object is to provide an improved electric switch of the character popularly useful in attachment plugs, lamp sockets, etc.

Referring to the drawings forming a part of this specification which are on an enlarged scale and in which like reference characters indicate like parts in all views:

Figure 1 is a front elevation of an end plug embodying my invention and

20 Figure 2 is a side elevation thereof.

Figure 3 is a plan view.

Figure 4 is an inverted plan view.

Figure 5 is a view of the plug as shown in Figure 1 with one half portion of the casing removed to reveal the assembled parts and shows the switch in contacting or "closed" position.

Figure 6 is an interior view of one of the half portions of the casing.

Figure 7 is a view similar to Figure 5 showing the position of the assembled parts when the switch is "open" and the circuit thru the plug is broken.

Figure 8 is a sectional view taken on lines 8—8 of Figure 7.

35 Figure 9 is a sectional view taken on lines 9—9 of Figure 7.

Figure 10 is a perspective view of the switch mechanism assembled as a unit and ready for insertion into the casing.

40 Figure 11 is a perspective view of one of the strip conductors of the plug having a terminal nut formed integral thereon to receive one of the wire-binding screws.

The plug casing 15 is made in two like half portions of moulded insulating material, such as hard rubber. Each half portion is recessed, as shown in Figure 5, so that when they are held together in assembled position by the screws 16—16, suitable passages, chambers, partitions and abutments are formed in the walls of the casing to properly receive and support the several parts assembled therein unattached to the casing.

Extending inwardly from the top of the casing 55 in communication with the chamber 21 is a cen-

tral circular passage 17 to admit a cable 18 containing current supply wires 19—19. An annular groove 20 in the wall of the passage 17 serves to receive the wire ring customarily employed for clamping the insulating material of the cable 18.

On each side of the plug adjacent the lower end of passage 17, binding screws 22—22 serve to fasten the inner ends of wires 19 to hexagonal nut-like terminals 23—23 removably seated in 10 pockets of similar outline moulded in the casing wall. The terminals 23 are formed integral with resilient strip conductors 24 and 25 respectively, which extend downwardly along the inner side walls of the casing on opposite sides of the plug. The strip 25 is substantially shorter than the strip 24 and is bent inwardly adjacent its free end, as shown in Figure 7. Spaced apart from the strip 25 on the same side of the plug is the free upper end of a metal strip conductor 26 which is also bent inwardly. As shown in the drawings, the free ends of the spaced resilient strips 25 and 26 overextend each other and are inwardly bent and flared apart in such manner as to provide 15 symmetrical and opposed resilient contacts adapted to be depressed and bridged by a switch element 43 to obtain a spring pressed engagement therewith.

The lower end of the conductor 24 is angularly bent and perforated for permanent attachment intermediate the upper ends of resilient conducting socket members 27 and 28 by means of a rivet 29 drifted integral with member 27, as shown in Figure 9. In the socket chamber, below the rivet, these socket members are bent away from each other and looped back so that they face in abutment for a considerable distance to provide a spring clip capable of receiving and firmly gripping a coupling prong inserted between them thru one of the apertures 30 in the base of the casing. When such a prong is inserted between them, the members 27 and 28 are forced apart against the spring resistance inherent in the material of which they are formed so that they will grip prongs of various shapes and diameters 45 over a large area, thus insuring good electrical contact and firm mechanical connection.

The lower end of the conductor 26 is formed similar to the conductor 24 and permanently attached to a like pair of socket members in a chamber formed on the opposite side of partition wall 31.

A pocket 32, shaped as shown, is recessed in the half portions of the casing to contain a U-shaped switch frame 33 which has slots 34—34 55

aligned laterally in its upwardly extending sides. Between the sides of the frame 33 is a switch member 35, the lower portion of which is reduced in width to provide shoulders 36—36 and the lower 5 end of which extends thru a hole in the base of the frame. A compression spring 37 surrounds the reduced lower portion of the member 35 and extends between abutments afforded by the base of the frame 33 and the shoulders 36 to support 10 the member 35 and press it upwardly against a symmetrical double cam 40. This cam is formed on the lower edge of sliding actuator 39 which extends thru a slot 38 in the member 35 and thru the slots 34 in the frame. The top edge of the 15 actuator 39 is cut away intermediate its ends to form shoulders 41—41 adapted to alternately abut the opposite sides of the frame 33 and thus limit its sliding movements.

The ends of the actuator are rounded and extend externally of the casing thru suitable openings in its opposite sides so that the actuator 20 may be manually operated. Adjacent its ends the actuator is marked "off" and "on" respectively, to indicate the condition of the switch.

25 An insulated arm 42 is fixed by one end at right angles on the upper end of the member 35 and a channel shaped contact element 43 is riveted over the other end of the insulated arm in position to bridge the bent free ends of the 30 resilient strip conductors 25 and 26.

As shown in Figure 7, the circuit thru the plug is open. To close it, actuator 39 carrying cam 40 is slid laterally by pressing in its projecting end marked "off". This movement of the cam forces 35 member 35 downwardly against the resistance of spring 37 until the apex of the cam has passed thru the slot 38, whereupon the compressed spring 37 instantly operates to thrust member 35 angularly upward against the opposite inclination of the cam into the closed position shown in Figure 5.

In plumping angularly upward in this manner, element 43 is caused to wipingly slide into bridging contact with the inwardly bent ends of the 45 resilient conductors 25 and 26. This wiping action keeps the several contacting surfaces clean and prevents arcing. The contacting pressure normally afforded by spring 37 is sufficient to compress the conductor ends slightly so that firm 50 spring pressed contact is assured.

To reopen the switch, the end of the actuator marked "on" is pressed in to repeat the foregoing movements in a substantially reverse manner. In breaking contact with the ends of the 55 conductors, the element 43 is caused to wipe downwardly against them before it is suddenly thrust upward into the open position.

Having thus described my invention, I claim as new:

60 1. An attachment plug comprising a casing, a strip conductor of resilient metal supported within the casing and having a free end transversely flared toward the central median line therethru, a second resilient metal conductor 65 supported within the casing having a free end transversely flared toward the central median line therethru, the flared free end of said second conductor being opposed, spaced apart and overextending the flared free end of said first conductor to provide symmetrical and opposed resilient contacts, a switch mechanism carried in 70 said casing having a contact element adapted to bridge the free ends of said conductors and to depress them against the yielding resistance inherent in the material of which they are formed

to obtain spring pressed engagement therewith.

2. An attachment plug comprising an insulated casing formed in two parts and having a central passage extending inwardly at its top, resilient metal conductors carried within said casing on opposite sides thereof, wire binding terminals carried by said conductors adjacent the inner end of said passage, said casing having chambers formed therein adjacent its base, a spring socket carried in each of said chambers, one of which 10 is connected to one of said conductors, the other said conductor having a free end bent toward the central median line thru the casing, a third resilient metal conductor supported in the casing having a free end bent toward the central median line therethru and opposed, spaced apart and overextending the bent free end of 15 said other free-ended conductor and attached at its opposite end to the other spring socket; each of said sockets comprising two strips of resilient 20 conducting metal held together at their conductor-connected ends, bent apart and looped back in facing abutment with each other to provide a spring clip, said casing having openings in its base positioned to admit attachment terminals receivable in said sockets; a switch mechanism carried in said casing comprising a switch member, a spring supporting said member adjacent one end thereof, a contact element carried by said member adjacent its other end, an actuator 25 supported for endwise sliding movements transversely of said member and having its opposite ends extending externally of the casing thru openings in its walls, a double cam carried by the actuator in engagement with said member 30 and adapted to first depress the member against the yielding resistance of said spring and then to guide the member angularly under the reciprocal pressure of the spring; said contact element being positioned and adapted to bridge the bent 35 free ends of said conductors and to depress them against the yielding resistance inherent in the 40 material of which they are formed.

3. An electric switch comprising flat resilient conductors spaced apart and each having a free 45 end overextending the other, said ends being inwardly bent and flared apart to provide symmetrical and opposed resilient contacts, and a switch member adapted to depress and bridge said contacts to obtain spring pressed engagement there- 50 with.

4. An attachment plug comprising an insulated casing having a central passage extending inwardly at its top, metal conductors carried within said casing, wire binding terminals carried by 55 said conductors adjacent the inner end of said passage, contact terminals carried by the casing adjacent its base, one of which is connected to one of said conductors, the other said conductor comprising a flat strip of resilient conducting metal having a free end flared toward the central median line thru the casing, a third flat strip conductor of resilient metal having a free end flared toward the central median line thru the 60 casing and connected at its opposite end to the other contact terminal, said flared free ends being opposed, spaced apart and overextending each other to provide symmetrical and opposed resilient contacts, and a switch mechanism carried in said casing having a member adapted to depress and bridge said contacts to obtain spring 65 pressed engagement therewith.

5. An attachment plug comprising an insulated casing formed in two complementary portions and having a passage extending inwardly at one end 70

thereof, the interior walls of said casing portions being recessed to receive and position the several internal parts of the plug in freely removable relation therefrom, said parts comprising: wire binding terminals positioned adjacent the inner end of said passage, contacts carried by the casing at its opposite end, a conductor extending from one of said terminals to one of said con-

tacts, and a manually operable switch mechanism adapted to complete a circuit between the other terminal and the other contact; and means for securing the casing portions together whereby the several internal parts are held assembled in operative relation.
